UNITED STATES PATENT OFFICE.

LAWRENCE P. WELFLEY, OF HINTON, WEST VIRGINIA.

GAGE-COCK.

1,076,727.

Specification of Letters Patent. Patented Oct. 28, 1913.

Application filed June 14, 1913. Serial No. 773,741.

To all whom it may concern:

Be it known that I, LAWRENCE P. WELFLEY, citizen of the United States, residing at Hinton, West Virginia, have invented 5 certain new and useful Improvements in Gage-Cocks, of which the following is a specification.

The present invention relates to improvements in gage cocks such as are commonly used on locomotive or other steam boilers.

The principal object of the invention is to provide a gage cock of the class described constructed in such a manner that the steam may be cut off from the main source and the 15 valve parts withdrawn for the purpose of cleaning or repairing without necessitating a reduction of the pressure.

A further object consists in so constructing the various parts as to avoid danger 20 of the gage cock becoming stopped up by the accumulation of mud, etc., which would render the device not only dangerous but inoperative.

With these and other objects in view, the 25 invention consists in the construction and arrangement of parts more fully described in the following specification, illustrated in the accompanying drawings and pointed out in the appended claims.

30 In the drawings Figure 1 is a transverse longitudinal view with parts shown in section; Fig. 2 is a vertical section taken on the line 2—2 of Fig. 1 looking to the left; and Fig. 3 is a similar view looking to the 35 right.

Referring by reference characters to the drawing, the gage cock comprises a valve casing or main body 1 connected to the pipe stem 2, the latter being provided with external screw threads 2^a by which it is permanently fitted into the boiler. A swivel connection is established between the parts 40 1 and 2 by means of a collar 3 or other suitable means which surrounds the enlarged head 2^b of the pipe stem, and is screw-threaded on the inner end of the valve casing, as shown at 3^a. The tapered valve 6 is located within the central chamber 7 of the casing, and in its closed position rests on the 45 valve seat 7^a formed therein. The valve stem 5 extends through the outer part of the casing in which it is screw-threaded, as shown at 4, and terminates in the handle 8 by means of which it is operated. Leading 50 from the chamber 7 is a central longitudinal passage 9 which, at the inner end of the

casing, terminates in a bell-mouthed chamber 10 having an outwardly flared wall. The pipe stem 2 is formed with a small longitudinal bore 11 inclined from the horizontal 60 so as to be constantly in register with the bell-mouthed chamber at a point near its outer periphery. A small metal lug 14 of substantially conical shape is built up within the wall of the chamber 10 at its periphery, 65 and is made integral with the main body 1. A pin 13 projects from the end of the stem 2 into the bell-mouthed chamber 10, and is positioned sufficiently near its outer circumference as to lie in the path of the cone-shaped lug, serving as a positive stop to limit the rotating movement of the valve 70 casing.

The parts 1 and 2, as have been described, are secured together with a swivel connection by the collar 3. The abutting vertical surfaces of the end of the stem 2 and the main body of the valve casing, including the end of the conical lug 14, form a ground joint, making any loss of steam by leakage 80 at this junction impossible, and prevents corrosion and accumulation.

A small outlet stem 15 is formed at right angles to the valve casing. This stem is provided with a vertical central bore 16 which 85 communicates with the chamber 7.

From the foregoing description the operation of the device is apparent. With the valve 6 open and the valve casing 1 turned in such position that the chamber 10 90 is in open communication with the port 11 of the stem 1, steam under pressure passes directly from the boiler through the port 11, chamber 10, port 9, chamber 7, and out the port 16. By turning the handle 8 the valve 95 6 seats itself upon the valve seat 7^a, and shuts off the steam from the outlet stem 15. Should the valve 6 need repairing or cleaning, it is only necessary to rotate the valve casing 1 until the conical lug 14 covers the 100 port 11, when the steam will be cut off without reducing the pressure at the boiler and the valve 6 can be removed entirely from the casing 1. The pin 13 acts as a positive stop limiting the rotation of the main body 105 1 for its open position with the port 11.

It will be noted that by inclining the port 11 so as to register with the chamber 10 near its outer circumference, open communication is assured between the two passages 11 110 and 9 during the greater part of the rotation of the valve casing. A further point of

vantage gained by forming the chamber 10 with an outwardly flaring wall is that accumulation of mud therein is precluded.

What I claim is:

- 5 1. A gage-cock comprising two parts, one part adapted to enter the boiler, the other part having a swivel connection with the first part and provided with an outlet port and a shut-off valve controlling same, one part being adapted to be rotated in relation to the other part for shutting off the steam independently of the shut-off valve, and means carried on the one part adapted to contact with the other part to limit the rotary movement of the other part after said closure has been effected, substantially as described.
- 10 2. A gage-cock comprising in combination a pipe stem permanently secured in a boiler, a main body portion having an outlet stem, a shut-off valve therefor, said main body portion and pipe stem having a swiv-
- 15
- 20

eled connection with each other, a central port within said main body leading from said valve and terminating in a bell-mouthed chamber, an inclined port within said pipe stem adapted to normally register eccentrically with said bell-mouthed chamber, a small built up lug formed integral with the wall of said bell-mouthed chamber, adapted to close communication between said inclined port of the stem and said bell-mouthed passage upon rotation of the body portion, and means carried by said stem portion to limit the rotary movement of said body portion after said closure has been effected, substantially as described.

In testimony whereof, I affix my signature in presence of two witnesses.

LAWRENCE P. WELFLEY.
